United States Patent Office

Des. 211,794
Patented July 30, 1968

211,794

ANTENNA

Robert M. Silliman, Silver Spring, Md., assignor to
Electronics Research, Inc., Evansville, Ind.

Filed Nov. 24, 1967, Ser. No. 9,531

Term of patent 14 years

(Cl. D26—14)

FIG. 1 is a perspective view of an antenna showing my new design;

FIG. 2 is a front elevational view;

FIG. 3 is a top plan view; and

FIG. 4 is a side elevational view.

I claim:

The ornamental design for an antenna, substantially as shown.
